MEANS FOR PROTECTING A BANK AGAINST ROBBERY

Filed Dec. 20, 1930 2 Sheets-Sheet 2

UNITED STATES PATENT OFFICE

STANLEY WERNER, OF MILWAUKEE, WISCONSIN

MEANS FOR PROTECTING A BANK AGAINST ROBBERY

Application filed December 20, 1930. Serial No. 503,792.

This invention relates to means for protecting a bank against robbery, and it is an object of the invention to provide an arrangement whereby a person doing business with a bank teller or other employee or officer of the bank is confined within an enclosure, and wherein entrance and exit from such enclosure is under control of the bank teller or other person.

10 Another object of the invention is to provide a device of this kind wherein a floor of a building is divided by a wall into two rooms, said wall being bulletproof in character and of a nature to effectively protect unauthorized access to any person or persons within one of the rooms, together with means in the second room for confining a person during the period he is doing business with an officer or employee of the bank within the first

20 named room.

It is also an object of the invention to provide an arrangement of this kind wherein means are afforded to effectively trap a person within a pit or well.

25 The invention consists in the details of construction and in the combination and arrangement of the several parts of my improved means for protecting a bank against robbery whereby certain important advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

40 Figure 1 is a fragmentary horizontal sectional view illustrating a means for protecting a bank against robbery constructed in accordance with an embodiment of my invention;

45 Figure 2 is a fragmentary view in rear elevation illustrating the means herein embodied for closing the operating circuit for the lock when the shutter is closed and also illustrating the means for maintaining the shutter raised;

Figure 3 is a view similar to Figure 2 showing the shutter raised;

Figure 4 is a fragmentary vertical sectional view taken substantially on the line 4—4 of Figure 1, said figure being also diagrammatic in character.

As disclosed in the accompanying drawings, W denotes the regular walls of a building structure providing a floor F. This floor F is divided into the two rooms A and B by a vertically disposed partition wall P. This partition wall extends entirely across the floor F from side to side wall W and also extends from the floor F to the ceiling C. This partition wall P is preferably of sheet iron of a thickness from between one-half inch to one inch although, of course, I do not wish to be understood as limiting myself in this respect as the thickness of the wall will depend upon the necessities and requirements of practice.

The room A is generally inaccessible by persons within room B and in order that proper ventilation may be had within room A one or more ventilators V are provided. These ventilators may be of any type preferred and, therefore, a detailed description and illustration thereof is believed to be unnecessary.

The partition wall P at a desired point thereon is provided with a window opening 1 which is normally closed by a solid metal shutter 2. This shutter 2, as herein disclosed, is supported by the guideways 3 for vertical sliding movement by an occupant of the room A and for which reason the lower portion of the shutter 2 is provided with a hand grasp 4. When the shutter 2 is raised it may be maintained in such elevated position in any manner desired. This means, however, in itself is of no particular importance insofar as the present invention is concerned.

The window opening 1 also has disposed thereover in any well known manner, the permanent bars 5 allowing a person to do business with an occupant of the room A through such opening 1 when the shutter 2 is raised or in open position, but of course preventing such person having such access through the opening 1 to obtain unlawful possession of any money or other articles.

which may be placed upon the conventional table or shelf 6 within the room A immediately adjacent to the partition wall P.

- 5 The window opening 1 opens within a booth or housing H, the side walls 7, the front wall 8, and the top wall 9 of which being also of sheet metal of requisite thickness. This booth or housing H is immediately adjacent to the partition wall P and, of course, a portion of such wall P forms the inner or back wall of the booth or housing H. The front wall 8 of the booth or housing is provided with an outwardly swinging door 10, said door automatically closing by one or more 10 suitably positioned spring hinges 11. The inner face of the door 10 carries a keeper 12 which, when the door is fully closed, automatically receives a locking bolt 14 comprised in a lock mechanism M.
- 15 20 This bolt 14 is projected or extended by a spring or in any other conventional manner and said bolt 14 is also of a solenoid type so that upon energizing of the associated field magnet or coil also comprised in the lock mechanism, the bolt 14 will be retracted sufficiently to allow the door 10 to be swung outwardly into open position so that a person may either enter or leave the housing or booth H.

- 30 35 40 This solenoid type of lock mechanism is of a conventional type and for which reason a detailed description and illustration is believed to be unnecessary.

- 45 The operating circuit a for this lock mechanism M extends within the room A and has interposed therein a switch 15 of a push button type and also interposed therein two relatively movable contact members 16 and 17. The contact member 16 is fixed to the wall P or other convenient support while the second contact 17 is carried by the shutter 2. When the shutter is fully closed the members 16 and 17 are in electrical contact but, as is believed to be obvious, during such periods when the shutter 2 is in raised or open position, the operating circuit a for the lock mechanism M is broken.

- 50 It is also at this time to be stated that the switch 15 is of a normally open type.

- 55 60 Suitably positioned within the room A is an audible signal 18, herein disclosed as a bell. The operating circuit b for this bell has interposed therein a normally open switch 19 arranged within the room B and preferably mounted upon the front wall 18 of the housing or booth H.

- 65 The door 10 is normally closed and when closed is locked by the bolt 14 against opening by a person outside of the booth or housing H.

- 70 75 80 A party desiring to do business with an officer or employee of the bank, who of course is in room A, such person who is in room B will first ring the bell 18 by operation of the switch 19, the bank employee will

then close the switch 15 resulting in retraction of the lock bolt 14 whereupon the customer may readily open the door 10 and enter the booth or housing H. After the customer makes such entrance the door 10 will automatically return to closed position. The bank employee, such as the teller, will then raise the shutter 2 so that he may conduct the desired business with the occupant of the booth or housing H. During the period this shutter 2 is raised, as before explained, the operating circuit a for the lock mechanism M is broken and, therefore, release on a retraction of the lock bolt 14 cannot be effected until after the shutter 2 has been returned to closed position.

85 90 95 After the business has been concluded with the customer the bank employee closes the shutter 2 and then again closes the switch 15 resulting in requisite retraction of the lock bolt 14, thus allowing the customer to make his exit.

100 105 110 The booth or housing H is erected directly above a well or pit W of a desired depth and the floor of the booth or housing constitutes a downwardly swinging trap door 20 which is normally maintained in its raised or effective position by a sliding bolt 21. This bolt 21, as herein disclosed, has operatively engaged therewith at a point within the room A a pedal 22 which, when operated by a person within the room A, will retract the bolt 21 and allow the trap door 20 to swing downwardly and thereby precipitate within the well or pit W a person confined within the housing or booth H. This is of particular importance in effecting the capture of a person endeavoring to rob the bank.

115 120 125 The shutter 2 may be maintained in any desired manner in its raised position but herein disclosed I provide a handle latch 23 secured to the partition 1 within the room A and which is adapted to engage a suitably positioned lug or finger 24 preferably positioned in close proximity to the lower margin of the shutter 2.

130 135 140 By the means for protection as hereinbefore described, it is believed to be self-evident that the bank employee is effectively protected against robbery and in the event a person occupying the booth or housing H should be guilty of any apparent or seeming unlawful act he can be confined within such booth or housing until outside aid has been obtained whereupon it will be a very easy matter indeed to effect the capture of such a party.

145 150 155 This application is partly in continuation of my already filed application Serial No. 499,597 filed December 2, 1930.

160 165 170 From the foregoing description it is thought to be obvious that a means for protecting a bank against robbery constructed in accordance with my invention is particularly well adapted for use by reason of the

convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a partition wall having an opening, a closure member for said opening arranged at one side of the wall, a booth at the opposite side of the wall and immediately adjacent thereto, the opening of the wall affording communication within the booth, a door for the booth, means for locking the door in closed position, and means at the same side of the wall as the closure member operable upon closing of the closure for releasing said door locking means.

2. In combination with a partition wall having an opening, a closure member for said opening arranged at one side of the wall, a booth at the opposite side of the wall and immediately adjacent thereto, the opening of the wall affording communication within the booth, a door for the booth, means for locking the door in closed position, and means at the same side of the wall as the closure member operable upon closing of the closure for releasing said door locking means, the means for releasing the lock mechanism being inoperative during the period the closure member is in open position.

In testimony whereof I hereunto affix my signature.
